WINDING MECHANISM

Original Filed April 12, 1921 2 Sheets-Sheet 2

UNITED STATES PATENT OFFICE.

WILLIAM H. PEARSON AND TIMOTHY J. KELLY, OF PASSAIC, NEW JERSEY, ASSIGNEES
TO BRIGHTON MILLS, A CORPORATION OF NEW JERSEY.

WINDING MECHANISM.

Original application filed April 12, 1921, Serial No. 460,725. Divided and this application filed December 1, 1921. Serial No. 519,258.

To all whom it may concern:

Be it known that we, WILLIAM H. PEARSON and TIMOTHY J. KELLY, citizens of the United States, residing at Passaic, in the county of Passaic and State of New Jersey, have made certain new and useful Improvements in Winding Mechanism, of which the following is a specification.

The invention relates to a novel mechanism for uniting threads or yarns in weaving or other textile or cordage work while avoiding forming a knot therein which involves the entire thread or yarn and maintaining or reestablishing at said juncture or place of union the amount of degree of twist which is normal or standard for the remainder of the thread or yarn.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a fragmentary view, partly in section and partly in vertical elevation, of a combined splicing and winding mechanism;

Fig. 2 is a fragmentary elevation, looking at Fig. 4 from the left;

Fig. 3 is a fragmentary detail of one form of device for lifting and supporting a reel or spool;

Fig. 4 is an enlarged, fragmentary detail on line 7—7 of Fig. 4;

Fig. 5 is a section on line 8—8 of Fig. 6;

Fig. 6 is a detached detail, partly in section, of the spool lifting device shown at the right-hand side of Fig. 4.

This application is a division of my co-

pending application Ser. No. 460,725 filed April 12, 1921, Patent No. 1,463,401.

In the weaving of many kinds of fabrics, and in other textile or cordage work, it is advantageous or essential that the ends of two threads or yarns be firmly and positively united without knots or like protuberances or irregularities and that the threads or yarns at the place of such union or juncture be maintained of substantially the normal or standard size and strength of the remainder of the thread or cord by re-establishing at the place of union the normal or standard amount or degree of twist.

In the above-mentioned application, Serial No. 460,725, a thread-uniting device is described in detail for delimiting two lengths of thread, untwisting each length, at which stage the respective strands are tied together so that the knots are well separated, and for then retwisting the thread into its original state. This invention is concerned particularly with improved spool holding and winding means, which may be used with the thread-uniting device described in the mentioned co-pending application, although capable of use in other situations.

In Figs. 1 and 2 a combined thread or cord splicing and winding machine is shown, and in the embodied form the winding mechanism has a plurality of winding devices arranged side by side in the machine, the splicing mechanism being movable to and from along the winding mechanism to bring it successively into convenient operative relation with any desired winding device.

So far as concerns many features of the invention, the winding mechanism may be of any desired or convenient form, and as shown herein the reels or spools are arranged horizontally and one above another, the thread or cord being wound from an upper reel or spool to another located below it.

Referring now to the details of the illustrated form of winding mechanism, this is shown in end view in Fig. 1 as of double construction, that is with one set of winding mechanisms facing to the right (shown in elevation) and another set of winding mech-

anisms, facing to the left, (shown partly in elevation and partly in section), all being mounted upon one machine frame.

As appears from Fig. 2, a plurality of sets of winding mechanisms or devices are arranged side by side in the machine frame, and a description of a single set or mechanism will be sufficient for all. Mounted on a frame piece 90 are a pair of upwardly and outwardly extending arms 91 and 92, having their outer ends recessed, as shown at 93 and 94, respectively, to support a rod 95 upon which a reel or spool 96 is mounted loosely so that the thread may be unwound therefrom.

Directly below the mechanism just described, as embodied, a pair of arms 97 and 98 extend from a sleeve 99, which sleeve is mounted to swing loosely on a rod or shaft 100, supported on the machine frame. The arms 97 and 98 are formed at their outer ends to hold a rod upon which the winding spool is mounted to rotate freely, the rod being movable to receive and discharge the spools. As embodied, this spool-supporting rod 101 is mounted in a recess in the end of the arm 97, and a pin 102 passes through the end of the arm and the rod, the rod being thus pivoted to swing outwardly, so that the spool or reel may be readily placed thereon and removed therefrom.

The arm 98 is cut away at its outer end (Figs. 1 and 3) to form a seat for the rod 101, and a hook 104 is pivoted at 105 on the arm 98, and is adapted to swing downwardly to hold the spool supporting rod 101 in position and to be swung upwardly to release the rod, so that the rod may be swung outwardly for the purpose of changing spools as described.

The winding is effected in the present embodiment by means of friction wheels or discs 106, which are located just beneath a reel or spool 107, mounted upon the rod 101, when in operative position. The wheel 106 contacts with the spool or reel 107, or with the cord or thread thereon, to rotate the spool and effect the winding operation. The wheel 106 is fixed on a shaft 107, journaled in the machine frame, the shaft being driven by any suitable driving means.

Means are provided in the embodied form for lifting the spool or reel 107 clear of the winding wheel 106 and maintaining it in this elevated or inoperative position during the changing of spools or reels. As embodied, referring first to Figs. 1, 2 and 4, a bracket 110 extends downwardly (Fig. 4) from the support 111 for the rod or shaft 100, and journaled in this bracket is a shaft 112, to which is fixed a hand lever 113. Fixed or integral with shaft 112 is a cam 114, positioned beneath the arm 98. When hand lever 113 is drawn downwardly and to the left from the position shown at the left

hand side of Fig. 4, the corresponding arms 97 and 98 are swung upwardly, lifting the spool or reel away from the winding wheel 106 to convenient position for changing the spools, and by moving the hand lever 113 to the opposite direction the spool is again brought down on the winding wheel.

A weighted arm 115 fixed to turn with arms 97 and 98 on shaft 100 is preferably employed to press the spool against winding wheel 106 to insure effective winding contact or friction, as shown at the left in Fig. 1. The arm 115 may also be utilized, as shown at the upper right hand side in Fig. 1, to hold the spool and spool holding arms in inoperative or idle position. For this purpose, the arm 115 will be swung backwardly beyond shaft 100 and will maintain the reel or spool 107 in elevated position until the entire device is swung outwardly and downwardly and arm 115 is again brought beyond shaft 100.

In Figs. 1 (right hand side) and 3 and 5, a different form of mechanism is shown for lifting the spool and its supporting arms for changing the spool or reel. In this form, a wedge or wedge-shaped cam 120 is mounted to slide longitudinally in a guideway 121 in the frame piece 122. A handle 122 projects downwardly or outwardly from the wedge 120. Both the inclination of the cam 120 and of the guideway 121 may be utilized to effect the lifting of the spool. When the handle 123 is pulled to the left in Fig. 6 the spool or reel 107 will be lifted to the inoperative position, that is, to stop the winding and to permit the spools to be changed, and when the handle 123 is pushed to the right in Fig. 3, the arms 97 and 98 are dropped down and the spool 107 is brought into winding relation with the winding or driving wheel 106.

In Fig. 2 the right-hand reel or spool 107 is shown in the raised or non-winding position, being retained in that position by its weighted arm 115. The two spools 107 to the left thereof are shown in winding position, that is, in position to be driven by the corresponding winding wheels 106.

In the present embodiment, the thread or cord splicing or uniting machine 125 is shown mounted to slide to and fro along in front of a plurality of the winding mechanisms, thereby being brought into convenient operative relation with any desired one of the winding mechanisms, and for this purpose, supporting and guiding bars 126 and 127 are disposed longitudinally along the frame of the machine. Bars 126 and 127 are employed to impose proper tension upon the thread as it is wound upon the spool 107. A reciprocating thread guide 128 is also usually employed to lay the thread evenly along the spool as it is wound thereon.

In this embodiment, the splicing or uniting machine 125 is mounted upon and so as to slide along the guide bars 126 and 127, whereby it may be used to splice the threads or cords therefor, and may be slid in front of any one of the winding devices, and may be used to splice the threads or cords therefor, and may then be slid in front of another of the winding device for this purpose, and 10 so on to and fro from one winding device to the other as may be required in the work.

In the present form, the base 130 of the splicing machine is extended, and the guide bars 126 and 127 are so positioned that the base 130 rests upon bar 126 and beneath bar 127, thereby forming the desired slideable support for the splicing machine.

The mechanism renders the work of winding much more easy and expeditious 20 and enables an operative to serve a larger number of winding mechanisms. It leaves the operative free to watch the winding mechanisms and to have both hands free for the work of splicing or uniting the threads 25 or cords. The splicer may by a simple movement of the hand be positioned with respect to any particular winding mechanism. The splicing mechanism need not be supported by the operative nor does it 30 require floor space nor to be moved about the floor from place to place.

In Fig. 6, and at the right in Fig. 1, a damping or braking device is shown for preventing the spool of thread 107 coasting or spinning as it is lifted from the friction driving roll 106. In connection therewith is shown a somewhat different form of the spool lifting cam, although the spool brake could be applied to any of the 40 spool raising devices. In this form of the spool raiser, a sliding cam 140 is slidably supported in a channeled guideway 141, supported on a bracket 142 fixed to the frame. This cam 140 engages beneath the 45 arm 98 in the same manner as cam 120, already described. A rod 143 extends outwardly whereby the cam 140 may be slid to and fro to let the spool down on to the driving roll 106 or to lift it therefrom. A leaf spring 50 144 is fixed to cam 140 and extends outwardly into frictional contact with the spool 107 and acts as a brake to prevent spinning or coasting of the spool when it is off the friction wheel 106.

The invention in its broader aspects is not limited to the specific mechanisms shown and described but departures may be made therefrom within the scope of the accompanying claims without departing from the 60 principles of the invention and without sacrificing its chief advantages.

What we claim is:—

1. In combination in a winding mechanism, means for rotating a spool, a pair of pivoted arms for supporting the spool, cam

means engageable directly with one of said arms for raising the spool out of contact with the spool rotating means, a device for manually operating said cam means, and a weight pivoted to move with the pivoted 70 arms for holding the spool in or out of contact with the spool rotating means.

2. In combination in a winding mechanism, a spool support, means for rotating the spool to wind the thread thereonto, a device movable to lift said spool from said 75 rotating means and to support it free therefrom, and a weight connected to the spool holder to support the spool free from said rotating means.

3. In combination in a winding mechanism, a spool support, means for rotating the spool to wind the thread thereonto, and a device manually movable to lift said spool from said rotating means and to support 80 it free therefrom, and a weight connected to the spool holder to support the spool free from said rotating means.

4. In combination in a winding mechanism, a spool support, means for rotating the spool to wind the thread thereonto, and a device movable to lift said spool from said 90 rotating means a desired distance and to support it in said position, and a weight connected to the spool holder to support 95 the spool free from said rotating means.

5. In combination in a winding mechanism, a spool support, means for rotating the spool to wind the thread thereonto, and a device movable to lift said spool from said 100 rotating means and to support it free therefrom, and a weight connected to the spool holder to press the spool to said rotating means and to support the spool free from said rotating means.

6. In combination in a winding mechanism, a spool support, means for rotating the spool to wind the thread thereonto, and a device manually movable to lift said spool from said 110 rotating means and to support it free therefrom, and a weight connected to the spool holder to press the spool to said rotating means and to support the spool free from said rotating means.

7. In combination in a winding mechanism, a spool support, means for rotating the spool to wind the thread thereonto, and a device movable to lift said spool from said 115 rotating means a desired distance and to support it in said position, and a weight connected to the spool holder to press the spool to said rotating means and to support the spool free from said rotating means.

8. In combination in a winding mechanism, rotating means for winding thread on a spool, a spool support having pivoted and connected arms, a member engaging one of said arms and slidably varying desired distances in a rectilinear path to con- 125 130

trol the operation of the rotating winding means on a spool on the spool support.

9. In combination in a winding mechanism, rotating means for winding thread on a spool, a spool support having pivoted and connected arms, a member engaging one of said arms and slidably varying desired

distances in a rectilinear path to correspondingly lift a spool on the spool support away from the rotating winding means.

10. In testimony whereof, we have signed our names to this specification.

TIMOTHY J. KELLY.

WILLIAM H. PEARSON.
